UNITED STATES PATENT OFFICE.

WILLIAM F. HUDGINS, OF DORRISVILLE, ILLINOIS, ASSIGNOR OF ONE-THIRD TO
FREDERICK W. BRISTOW AND ONE-THIRD TO SQUIRE A. WALLACE, BOTH OF
DORRISVILLE, ILLINOIS.

LAMP.

1,079,347.

Specification of Letters Patent. Patented Nov. 25, 1913.

Application filed January 25, 1913. Serial No. 744,213.

To all whom it may concern:

Be it known that I, WILLIAM F. HUDGINS, a citizen of the United States, residing at Dorrisville, in the county of Saline and State 5 of Illinois, have invented certain new and useful Improvements in Lamps, of which the following is a specification, reference being had to the accompanying drawings.

This invention relates to improvements in 10 lamps and more particularly to that class of lamps which are adapted to burn acetylene gas.

The invention is directed especially to the provision of a lamp of the acetylene type 15 which is adapted for use as a miner's lamp, but it may also be used as a vehicle lamp or for other purposes.

An object of this invention is the provision of means for straining the gas before it enters the burner tube, to prevent the tube from becoming clogged and thus hindering the flow of gas and rendering the lamp inoperative.

A further object of this invention is the provision of a lamp of this character, to 25 which is secured an oil burner, the wick of the oil burner being disposed adjacent the burner nipple of the acetylene lamp to form a pilot light whereby the acetylene lamp 30 may be lighted without the use of matches.

With these and other objects in view, my invention consists of certain constructions, combinations and arrangements of parts to be hereinafter more fully described, claimed, 35 and illustrated in the accompanying drawing, in which,

Figure 1 is a front elevation of my device; and Fig. 2 is a section on the line 2—2 of Fig. 1.

Referring more particularly to the drawing, the numeral 1 designates the carbide 40 container which is provided with a threaded neck 2 which is adapted to engage the threaded flange 3 of the water reservoir 4. A gasket 45 is disposed on the neck 2 of the carbide container and the lower edge of the flange 3 of the water reservoir is adapted to engage the gasket to form a gas-tight connection between the members. A filling opening 6 50 is formed in the top of the reservoir, the opening being closed by a cap 7. A central threaded opening 8 is formed in the top of the water reservoir, through which extends a valve rod 9, the rod being threaded on its

upper end for adjustable engagement with 55 the threads in the opening 8. The bottom plate 10 is also provided with a central opening through which the rod 9 is adapted to extend. A cup-shaped member 11 is connected to the bottom face of the plate 10, 60 the cup being also formed with a central opening through which the valve rod 9 extends, and secured to the bottom face of the plate 10 and extending through the central opening in the cup 11 is a water tube 12 65 which is adapted to convey water from the reservoir to the container. The lower end of the tube 12 is tapered as at 13, and the lower end of the rod 9 is also tapered as at 14 to form a tightly closing valve for cutting off the supply of water from the reservoir to the container. A tubular distributor 15 is secured to the lower face of the cup 11, and is adapted to extend downwardly within the container, and is provided with 70 a plurality of openings through which the water may pass to the carbide. Connected to the upper face of the plate 10 is a tubular conduit 17 which extends through the wall of the water receptacle, and secured to the 75 end of the tube is a burner nipple 18 which may be of any desired construction. A reflector 19 is secured to the exterior wall of the reservoir around the burner nipple to increase the glare of the flame.

A plurality of openings 20 are formed in the cup 11, the gas from the container being adapted to pass through the openings and thence into the tube 17 to the burner. To prevent clogging of the burner, a disk of 80 felt or other absorbent material 21 is arranged within the cup, to prevent any small particles of carbide or any other foreign matter from passing through the cup to the burner nipple.

An oil font 22 which may be of any desired construction is secured to the water reservoir by straps 23, the wick tube 24 of the font being arranged adjacent the burner nipple 18. A suitable filling opening 25 is 100 formed in the font which is closed by a cap 26, and a wick operating rod of any desired construction is secured to the wick tube for adjusting the wick in the ordinary manner.

In use, the miner lights the wick of the oil burner before entering the mine, and when it is desired to light the acetylene

105

burner; it is only necessary to operate the valve rod 9 so as to allow water to enter the container from the reservoir, and the acetylene burner will be automatically lighted immediately upon generation of the gas.

In the ordinary miner's lamp, when the carbid container is removed to replenish the supply of carbid, the miner is left in complete darkness. In a device constructed in accordance with my invention, the wick of the oil burner may be raised so as to be lighted from the flame of the acetylene burner, whereupon the carbid container may be removed and the miner will have sufficient light to readily fill the container. Upon again securing the container to the reservoir, the wick may be lowered and extinguished until it is again desired for use.

What I claim is:—

A device of the character described comprising the combination of a carbid lamp having a reduced portion, an auxiliary lamp removably secured to such reduced portion of the carbid lamp and having an upwardly directed burner, a reflector carried by the carbid lamp, and an outwardly directed burner for said carbid lamp extending through the wall thereof and through the reflector, said burner terminating adjacent the burner of the auxiliary lamp.

In testimony whereof I hereunto affix my signature in the presence of two witnesses.

WILLIAM F. HUDGINS.
